DISPLAY DEVICE

Jay M. Johnson, Detroit, Mich.

Application December 12, 1940, Serial No. 369,794

4 Claims. (Cl. 40—32)

My invention pertains to illuminated sign display devices and more particularly to moving sign exhibiting devices of the type having an endless sign bearing strip or film which moves in front of a light source for displaying the signs or indicia carried thereby.

Such moving sign exhibiting apparatus can be used for the display of a series of messages or pictures of considerable length, number and variety, for advertising and other purposes. When used for advertising and selling, light, color and action are very effectively utilized in telling the sales story, and such devices are very effective silent salesmen. For such purposes the apparatus is left operating in store windows, adjacent, on or in the goods or furniture being advertised, and it must be capable of moving and illuminating the display strip hour after hour, day and night without human attention. It is therefore very important that the apparatus be so constructed that it will be compact and simple in construction and will store and exhibit a long length of the display strip for long periods of time without binding, sticking or overheating. It is also very important that the display film may be changed quickly and conveniently.

It is accordingly an object of my invention to provide an improved illuminated moving sign display device of a compact rugged construction which stores a large quantity of display strip which it delivers and exhibits in a smooth free flowing movement.

It is also an object of my invention to provide a moving sign exhibiting device comprising an improved cooling and ventilating arrangement for dispersing the heat generated by the compactly enclosed and assembled motor, light source and other elements.

It is a further object of my invention to provide in such a display device an improved combination of a friction drive in combination with a film coiling well arranged for smoothly coiling and delivering a large quantity of display film.

Another object of my invention is to provide such a movable illuminated display device in which display strips may be quickly and conveniently inserted, replaced or exchanged.

A further object of my invention is to provide such a movable sign exhibitor of a compact, simplified construction comprising a unitary base assembly which may be conveniently prefabricated before it is enclosed and mounted in the housing.

Further objects and advantages are within the scope of my invention, such as relate to the ar-

rangement, operation and function of the related elements of the structure, to various details of construction and to combinations of parts, elements *per se*, and to economies of manufacture and numerous other features as will be apparent from a consideration of the specification in conjunction with the drawings disclosing a specific embodiment of my invention, similar reference characters being applied to corresponding elements throughout, and in which:

Fig. 1 is a front elevational view showing one embodiment of my improved illuminated moving sign exhibiting device;

Fig. 2 is a plan view looking down on the display device with the cover removed to show the internal arrangement of the elements mounted upon the base in the casing;

Fig. 3 is a longitudinal sectional view through the device taken along line 3—3 in Fig. 2;

Fig. 4 is a cross-sectional view on line 4—4 of Fig. 3, with the cover on;

Fig. 5 is an enlarged detail view of one of the film guide spindles and the pivot support;

Figs. 6 and 7 are detail views showing the film guiding strips and the drive roll; and

Fig. 8 is an enlarged perspective view showing arm 37.

Referring more specifically to the figures of the drawings, I have illustratively disclosed one embodiment of an illuminated moving sign strip exhibiting device constructed in accordance with the principles of my invention and comprising an enclosing housing or casing 11 which may be constructed of any suitable opaque material, such as sheet metal selected of a gauge suitable to provide the desired strength and rigidity, and externally finished in any well known manner to present a pleasing ornamental appearance.

To provide a simple compact construction the enclosing housing 11 is preferably of a generally rectangular conformation open at the top and bottom and having an elongated display window 13 opening along one side wall, which may be termed the front wall. Bent inwardly from the

lower edges of the front and back walls of the casing are inturned flanges 15 and these are suitably apertured to receive rubber pads or feet 17 which are pressed therethrough and serve for mounting the device on furniture or other articles without danger of scratching or marring the finish.

A strip of metal 19 is secured, as by spot welding, around the inside of the open top of the housing 11 where it serves to receive a cover 21 which fits snugly down thereover abutting the

upper edges of the walls of the housing. The cover 21 is also provided with an elongated air baffling and light reflecting wall member 23 which, as shown in cross-sectional view Fig. 4, is secured to the under side of the cover and projects down into the housing in spaced relation behind the front wall and window, for a purpose to be subsequently described. From one end of the baffle 23 a portion 25 projects forward in L shaped relation.

The operative elements of my display device are conveniently preassembled upon a base wall member 27 and the simple compact base unit is then inserted into the housing where it is mounted or secured in any suitable manner, as by lateral edge flanges 29 which are secured to the walls of the housing below the window level, as by welding. The preassembled base unit carries the following elements mounted in cooperative association.

The light source 31 utilized for illuminating the display strip is preferably one of the types of electric lamps available in an elongated tubular form. This lamp 31 is mounted in a closely spaced position behind the display window opening 13 in the front wall of the housing and is supported between a pair of suitable socket members 33 which are secured by screws 35 to the under side of the base extending upwardly through and above the upper side of the base. The lamp socket brackets 33 are mounted in such a manner that the terminals are positioned for connecting the wires 39 in the space under the base wall.

For receiving and guiding a moving flexible display strip or film 40, a plurality of spools or spindles 41 are rotatably journaled upon stationary pivot pins 43 which rise from the base in suitably spaced positions. As shown in Fig. 5, spaced slightly above the lower end on the pivot pins 43 is a flange 45 of enlarged diameter which abuts the upper side of the base wall 27 as the lower end of the pivot pin is passed through a suitable aperture in the base wall. The lower end of the pin is peened for securing it firmly in the base. The film guide spools may be made of any suitable plastic composition, such as cellulose acetate, although these may be made of wood or other suitable material. When the spindle 41 is made of plastic composition it is preferably made in an upper part 47 having a smooth downwardly extending stem 49 having an upper rim 50, against which the film runs with the upper edge under a flange 50'. On the lower end of the stem 49 a lower rim 51 is pressed and cemented. The upper end of each spool is provided with an enlarged concentric aperture 53 for enclosing a retainer 55 which is a resilient wire fastener of a U-shape which is sprung into a circumferential groove on the upper end of the pivot pin 43. The flange 45 on the lower end of the pivot 43 also serves to journal the spool spaced above the base wall. Two of the guide spindles 41 are spaced on opposite sides of the window so that the moving display strip passes between the window and the light source to be viewed externally. A strip of translucent material 57 is mounted between brackets 59 rising from the base and disposed between the light source 31 and the display strip 40 to provide uniform illumination, and serving as a screen for protecting the film from direct radiated heat from the lamp.

The motive unit consists of a suitable small electric motor 61 mounted in an opening in a rectangular base plate 63 which is inserted in a close

fitting aperture in the base wall 27 where it is secured as by screws 65 passing through lugs or flanges 66 from the base wall 27. Fiber washers 67 are disposed under the screw heads. Members 69, of vibration absorbing material, such as rubber or cork, are inserted between the base plate 63 of the motive unit and the lugs from the base wall 27 of the casing so that the mechanism unit is practically floating on rubber for quiet operation. Lugs 71 extend laterally from the motor and are secured to the under side of the base plate 63 mounting the motor with its shaft 73 below the base plate. A directly connected air impeller 75 is also mounted on the opposite end of the motor shaft for ventilating the unit. For this purpose a sirocco type blower is preferably utilized and a scroll housing 77 is mounted in the base plate 63 and provided with an air conduit apron 79 so that the intake port opens above the base. The discharge outlet 78 is disposed to open below the base, as may be seen in Fig. 4.

In this arrangement the blower 75 is operated continuously so long as the display unit is operated, drawing air from the space above the base 27 for carrying the heat away from the motor, the light source and other elements, and discharging the heated air into the space below the base wall from whence it escapes to the outside atmosphere. Cool ventilating outside air enters the space above the base through the window opening 13 because the moving display strip 40 is loosely disposed against the edges of the window and the flexibility of the strip freely admits air therethrough. As the air enters the window, the L-shaped reflector member 23 behind the lamp deflects the air to flow out around one end circulating around in the space above the base wall to receive the heat therein generated by the enclosed elements after which the heated air passes into the blower and is discharged below the base wall. The circulation of the cooling air is represented by the curved arrows. The rubber pads 77 under the housing 11 support the lower edges in spaced relation above any surface 80 whereon the display unit may be installed, and the heated air exhausted into the space under the base wall can freely escape. Louvres 81 may also be provided in the lower portion of the rear wall to discharge heated air.

For moving the display strip, a soft rubber spool 83 is provided which is mounted upon and secured firmly to a drive shaft 85 by a nut 87 and the shaft extends vertically down through the motive base plate 63 wherein it is rotatably journaled in a suitable bearing. The lower end of the vertical shaft carries a worm wheel 89 which meshes with a worm 91 secured on the extended motor shaft 73 under the base for driving the rubber strip moving spool 83 at a substantially reduced speed. To hold the display strip 40 closely engaged against the rubber drive spool, a guide spool or spindle 91 is rotatably mounted upon a vertical pivot shaft 93 which at its lower end passes down through a slot 95 in the base plate 63 and is attached to and carried by the end of a swinging arm 97 which turns on a stationary pivot 99 projecting down from the base plate. A coiled spring 101 is concentrically disposed upon the stationary pivot shaft 99 with one end of the spring reacting on the arm 97 and the other end secured in the base plate 63 so that the arm is at all times urged to rotate or swing to carry the guide spool 91 toward the soft rubber drive spool 83 to maintain high friction driving con-

tact between the display strip 40 and the soft drive spool 83. The film or display strip 40 is moved in the direction indicated by the straight arrows shown adjacent thereto.

A film coil well 103 of a generally cylindrical conformation, closed by a circular end wall at the bottom end, is mounted in a circular opening provided in the base member 27, where it is secured, as by flaring the upper edge. The film well 103 projects downwardly into the space below the base 27 and the circular bottom wall 105 of the well has a raised circular central portion 105' for smoothly guiding the rotation of a coil of the excess film therein. Reinforcing ribs 107 are also raised from the bottom wall extending radially outward from the raised central portion. The metal of the film well is prefinished nickel steel or any other suitable material having a smooth finish to minimize friction with the coil of film as it rotates and the reinforcing ribs, by holding the coil up from the bottom, serve also the purpose of still further reducing the friction.

A film guide is provided comprising a pair of curved light metal strips 109 and 111 arranged to provide for an even free flow of the film from the drive roll into a rotating coil formed on the bottom of the film well where a very large quantity or length of the extra slack film may be stored. For this purpose the two curved guide strips are secured together by an inverted U-shaped bracket 113 passing over the upper edges of the strips with the legs passing down over and secured to the outer sides of the two strips as by rivets 115. The leg of the bracket 113 adjacent the back wall of the housing is extended down and then turned laterally to provide a lug or tab 117 abutting the base wall 27 whereon it is firmly secured by a retainer pin 119 the lower end of which is threaded and passes through aligned apertures in the tab and base and screws firmly into a nut 121 soldered on the lower surface of the base wall. The retainer pin or stud 119 has a flange 123 spaced up from the lower end sufficiently for bearing down on the upper surface of lug 117. A pilot pin 125 rising from the base provides proper alignment. The upper end of the retainer pin is provided with a knurled portion so that it may be quickly and conveniently released and the film guides 109 and 111 removed for changing the film. The front guide strip 111 extends approximately half of the way across the film well at a position about one-fourth of a diameter from the rear side of the well, and the end is curled toward the center. The rearward film guide strip 109 extends in slightly spaced relation behind the other strip and it is substantially longer. From the point where rear guide 109 passes the front to back diameter of the film well it is curved forwardly and downwardly in a generally circular or helical manner and substantially concentrically with reference to the cylindrical side walls of the film well. The extended portion of the long outer guide strip 109 is attached, as by rivets, to an L-shape bracket 127 the lower leg of which extends out over the base wall where it is secured by a retainer stud 129 passing therethrough into a nut under the base wall 27 similarly to the other retainer stud 119 previously described. The upper end of the vertical leg of the bracket 127 extends above the upper edge of the guide strip 109 and is bent over toward the center of the film well 103. The guide strips are provided with a pair of raised beads or ribs 131 for reinforcement and which also prevent the film face rubbing on the guide. The ends of the two film guide strips 133

109 and 111 are inserted between the drive roll 83 and the guide spindles 91 and film from the drive pulley passes between the two guide strips as is shown more clearly in Fig. 6. The film is then guided to coil down into the film well 103 where a substantial number of turns of film may be coiled, rotating on the bottom wall of the film well by force derived from the moving film. The film from the motive unit enters the center of the coil and, after rotating in the well a number of times corresponding to the number of turns in the coil, the film passes from the well through a runway 133 which inclines upwardly from the well to the base wall 27 wherein it is secured.

A two conductor electric cord 135 connected to the terminals of the motor is passed out of the housing through an insulating bushing 137 in the lower portion of the back wall of the housing and by means of a usual two contact plug the device may be conveniently plugged into any convenient electric service outlet. The electric lamp 31 for convenience may be energized in parallel with the electric motor 61 through wires connected from the terminals of the motor and extending under the base wall to the terminals of the lamp sockets 33 which are disposed under the base wall for convenient connection, and so that all connections and wires are concealed.

Operation of the electric motor drives the soft rubber drive pulley or spool 83 against which the display strip or film 40 is softly pressed by the swinging spring biased spool 91. The film 40 is moved by the drive roll 83 in the direction shown by the arrows, and passing the drive roll it is pushed around the downwardly curving guide strip into the inner turn of the coil in the film well. From the well the film emerges from the outer turn of the coil passing up the runway, passing around the freely rotating guide spindles 41, thence through the space between the lamp and the window around the guide spindles 41, completing the circuit of travel to the drive unit. During the time that the film is coiled in the film well it rotates on the bottom of the film well sliding quite freely over the smooth reinforcing ribs 107 raised therefrom which also reduces friction by holding the lower edge of the film from engaging the extensive surface of the bottom wall. The film is rotated in the film well by energy derived from the moving film pushed into and pulled from the well. As soon as the electric motor is started and so long as it operates, the directly connected blower 75 is operated which draws cooling air into the upper portion of the housing through the window opening 13 around the flexible film 40. The cooling air then circulates around the baffle 23 and around the interior of the upper space in the housing, as shown by the curved arrows, to absorb heat from the elements therein enclosed which is then discharged under the base wall from whence it escapes to outside atmosphere.

When new copy is to be inserted this is very quickly and conveniently accomplished merely by releasing the two retainer studs 119 and 129 and lifting the guide strips 109 and 111 out of the well after which the film or display strip is easily lifted from the movable illuminated sign exhibitor and a new film inserted therein.

It is apparent that within the scope of the invention, modifications and different arrangements may be made other than herein disclosed, and the present disclosure is illustrative merely, the invention comprehending variations thereof.

I claim:

1. In an illuminated moving sign exhibiting device, an endless flexible display strip, a casing of opaque material having an elongated display window opening, motive means in said casing, means driven by said motive means for moving said display strip in said casing past said display window, an elongated lamp in said casing for projecting light through said display strip and window, a blower for drawing air in through the window and discharging air from the casing, and a baffle reflector strip in said casing disposed behind the light source for reflecting light out through the display window and the adjacent portion of the moving display strip while also serving to baffle the cooling air to circulate from the window around the interior of the casing to carry heat from the elements enclosed therein.

2. In an illuminated exhibiting device, an endless flexible display strip, a casing of opaque material having a display window opening, motive means in said casing, means driven by said motive means for moving said display strip in said casing past said display window, light emitting means in said casing for projecting light through said display strip and window, a blower driven by said motive means, air flow conduit and baffle means so arranged that the blower draws air from the space adjacent the light source and window for drawing fresh cooling air into the window around the flexible display strip and circulating the cooling air in said space to carry heat away from the enclosed elements.

3. In an illuminated display device, a casing of opaque material having an elongated display window opening through one side wall, a base wall mounted in said casing, a plurality of vertically disposed rotative spindles supported by said base wall and arranged to receive and guide

10 a moving flexible display strip past said display window in edgewise relation to said base, motive means on said base, means driven by said motive means for moving said strip, a light source in said casing for projecting light through said display strip and window, a blower driven by said motive means, air flow conduit and baffle means so arranged in connection with said blower that the blower draws air from the space on the side of the base adjacent the light source and window for drawing fresh cooling air into the window around the flexible display strip and circulating the cooling air in said space to carry heat away from the enclosed elements.

15 20 25 30 35 4. An illuminated moving sign exhibitor comprising, an opaque casing of a generally rectangular conformation, said casing being open at the top and bottom and having an elongated display window opening along one side wall, a base member inserted into said casing and secured below said window, an electric light source mounted on said base for projecting light through said display window, a plurality of rotative spindles supported by said base for guiding a flexible display strip to move in edgewise relation to the base and pass between the window and the light source, an electric motor mounted on said base, drive means actuated by said motor for moving said strip, a blower driven by said motor, said blower being mounted on said base with the intake and discharge ports connected for drawing air from the space above the base and discharging it below the base, a cover for closing the open top of said casing, and an air baffling light reflecting member secured to and projecting down from said cover to be positioned at the rear of the light source when the cover is applied on the casing.

JAY M. JOHNSON.
